UNITED STATES PATENT OFFICE.

DAVID W. HAWKSWORTH, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CARLINE.

Application filed July 9, 1921. Serial No. 483,383.

The invention relates to carlines and consists in the novel construction by which the metal of the blank is advantageously used, particularly to obtain a strong connection 5 with the plates of the car frame. The invention also comprises a construction of clip which is used in combination with the carlines as a securing means therefor, as more fully hereinafter set forth.

10 In the drawings:

Figure 1 is a plan view of a portion of a car roof frame showing one half of the carline secured thereto;

15 Figure 2 is a vertical cross-section through the car roof showing the carline in elevation;

Figure 3 is a side elevation illustrating the manner of attaching the carline to the side plate;

20 Figure 4 is a perspective view of one end of the carline; and

Figures 5 and 6 are similar views of the securing clips.

In general cross-section my improved carline is a Z-bar having a vertically extending web portion A, a laterally extending bottom B and the oppositely laterally extending top flange C. The flange B is of uniform width and extends horizontally from end to end 25 of the carline or between the side plates D of the car frame. The web portion A is of greatest width at the center of the car and tapered towards the side at an angle corresponding to the pitch of the roof. The top flange C is widest at the opposite end of the carline or adjacent to the side plates of the car frame and tapers towards the center. Thus the structure is one which can be 30 formed from a rectangular sheet-metal blank, the side edges of which are originally 35 parallel.

To use advantageously all of the metal of the original blank, the wide end portions of the top flange C are utilized for attachment 40 to clips which secure the carline to the side plates. These clips comprise the outer and inner clip members E and F, which are angle-shaped and are of a width corresponding 45 to the combined width of the top and bottom flanges of the carline. Each clip has a vertical portion, such portion G of the clip E extending downward outside of the plate D and a corresponding portion H of the clip F extending downward on the inner face of 50 the plate D. Both flanges are apertured in

registration with each other and bolts I which pass through the side plate and apertures in the clips clamp the same rigidly in position. The laterally extending flange J of the clip E has a portion J' which conforms to the pitch of the roof and a horizontal portion J² which overlaps the top flange of the carline and is secured thereto by rivets K at opposite sides thereof. The clip F is provided with a horizontally extending flange L corresponding in width to the top flange of the carline and underlapping the same, and a horizontally extending flange M of the width of the bottom flange of the carline underlapping this flange. The 60 original shape of the blank is rectangular and the extra metal in the flange M, due to its being struck out from a lower plane, is utilized to underlap the flange B a greater 65 distance and to place the rivet hole a greater 70 distance from the vertical flange. This also facilitates the assembly of the structure as the rivet hole N in the flange M will clear the flange J² of the clip E, said flange having a bevelled corner as shown.

75 The web A of the carline from its end adjacent to the side plate to a point adjacent to the first purlin is of uniform height and this, by reason of the pitch in the roof, will provide a spacing between the top flange and 80 the roof-boards O sufficient for receiving the purlins P. The top flange C has parallel side edges for this portion of the carline and also has parallel sides at the center where the ridge pole is supported upon the carline. 85 Between these parallel portions the top flange is tapered as shown. Thus, every bit of the metal of the original blanks both for the carline proper and the two clips is utilized in increasing the strength and rigidity 90 of the structure.

95 What I claim as my invention is:

1. A carline comprising a Z-bar developed from a sheet-metal blank of uniform width to have a web portion and a flange portion 100 reversely tapered between the ridge and the side plates, and a clip for securing said carline to the side plate of a width equal to the combined width of the top and bottom flanges of the Z-bar in the widest portions 105 thereof, said clip being secured to the inside of said side plate and having portions at different elevations secured to said flanges.

2. A carline comprising a Z-bar developed from a sheet-metal blank of uniform width 110

to form a bottom flange of uniform width extending from side plate to side plate of the car frame, a web portion tapering between the ridge and the side plates, and a top flange which reversely tapers between the side plates and ridge, and a clip for securing said carline to the side plate having a width equal to the combined width of the top and bottom flanges thereof and having laterally extending portions in planes corresponding to said top and bottom flanges and riveted thereto.

3. A carline comprising a Z-bar developed from a blank of uniform width to form a bottom flange of uniform width extending horizontally between side and side plate of a car frame, a web portion which tapers between the ridge and side plate and a top flange which reversely tapers from the side plate to the ridge, a pair of clips for embracing the side plate, said clips being of a width corresponding to the combined width of the top and bottom flanges at the end of the carline and respectively provided with portions overlapping and underlapping said flanges and secured thereto, said clips also having vertical portions respectively adjacent to the outer and inner faces of the side plate with apertures therein registering with each other and with apertures in the side plate for the passage of clamping bolts.

4. A carline comprising a Z-bar having a web portion tapering from the ridge to the side plate and a top flange which is reversely tapered, and clips equal in width to the combined width of the top and bottom flanges of said Z-bar having laterally extending flanges respectively overlapping and underlapping the same and riveted thereto with vertical flanges respectively adjacent to the inner and outer faces of the side plate.

5. A carline comprising a Z-bar having a bottom flange of uniform width, a web portion tapering between the ridge and the side plate and a top flange reversely tapering between the side plate and ridge, clips for embracing the side plate having inwardly extending portions respectively overlapping and underlapping the flanges of the carline, said clips being of a width equal to the combined width of said top and bottom flanges of the carline and the inner clip having laterally extending portions in planes adjacent to both top and bottom flanges of the carline, the latter portion underlying the carline flange to a greater extent and secured thereto at a point clearing the flange of the other clip.

In testimony whereof I affix my signature.

DAVID W. HAWKSWORTH.
